Patented Oct. 26, 1909.

FIG. 2.

FIG. 3.

UNITED STATES PATENT OFFICE.

EDWARD AUGUST MAISCH, OF ANDERSON, CALIFORNIA.

INCUBATOR.

938,260.

Specification of Letters Patent. Patented Oct. 26, 1909.

Application filed January 23, 1909. Serial No. 473,862.

To all whom it may concern:

Be it known that I, EDWARD AUGUST MAISCH, a citizen of the United States, and a resident of Anderson, in the county of 5 Shasta and State of California, have invented a new and Improved Incubator, of which the following is a full, clear, and exact description.

This invention relates to certain improvements in electrically heated incubators, and more particularly to the construction of the heating coils and the egg-supporting trays.

A further important feature of the invention relates to the means for automatically 15 maintaining the temperature constant.

Reference is to be had to the accompanying drawings, forming a part of this specification, in which similar characters of reference indicate corresponding parts in all 20 the figures, and in which—

Figure 1 is an end view of an incubator constructed in accordance with my invention, the door and door jamb thereof being removed; Fig. 2 is a top plan view of one of 25 the heating coils; and Fig. 3 is a side elevation of my improved heat-regulating mechanism.

The walls of my improved incubator may be formed of any suitable material, and the 30 incubator may be made of any suitable size, but for purposes of illustration, I have shown the body or walls of the incubator in the form of a wooden box having side walls 10, a top wall 11, and a bottom wall 12.

Within the incubator I mount a plurality 35 of coils of electric wire, which serve as the heating coils, and adjacent each heating coil is a tray, shelf, or support for the eggs. These coils and also the trays are readily 40 removable and both are preferably supported from the same cleats or guideways.

As shown, the two side walls have cleats or 45 guiding and supporting strips 13 secured to the inner surface thereof and arranged in pairs upon substantially the same level. The strips of each pair serve to directly support a tray or shelf 14 upon which the eggs are placed, and in the opposed faces of the two cleats are grooves within which slides the 50 support for the heating coils. This support, as illustrated, comprises a frame 15 of wood, or metal properly insulated, of a width slightly less than that of the incubator, and slidably mounted in the grooves in the cleats 55 13, so as to be normally disposed substan-

tially parallel to the shelf or tray supported by the same cleats. The frames 15 serve to support the heating coils which are wound about the same lengthwise of the incubator, so that the wires of the successive turns lie 60 parallel to each other and parallel to the supporting cleats 13. The wires of the heating coils thus present grids of parallel wires, and each heating coil serves to heat the tray below as well as the tray above. The trays 65 or shelves 14 may be readily removed from the cleats 13 and by disconnecting the wires the heating coils may also be readily removed.

The heating coils are connected in parallel with an electric lighting circuit or any other suitable source of electrical energy, that illustrated being merely a battery 17. Within the circuit is included a regulator for automatically controlling the current. 70 This regulator is controllable from the outside and is of the form illustrated in Fig. 3. One terminal of the electric circuit is connected to a cup 18 containing mercury, and the other terminal is connected to the pivotal support 19 of a rod or bar 20. One end of the rod is adapted to dip into the mercury and the other end of the rod carries a counterbalancing weight 21.

Within the incubator is a thermostat 22 85 formed of two separate pieces of metal having different co-efficients of expansion and rigidly secured together. The thermostat is rigidly supported at one end and its free end tends to swing upwardly upon an increase in 90 temperature. The free end of the thermostat carries a rod 23 which may engage with the lower end of a regulating screw 24 carried by the rod 20, so as to lift the end of the rod out of the cup of mercury. Thus, 95 as the temperature increases beyond a predetermined limit, the circuit is broken by the lifting of the rod 20 and no more current will flow through the heating coils until the temperature has been reduced to the 100 desired point. The temperature at which the circuit will be broken may be readily controlled by adjusting the position of the regulating screw, so that it will contact with the rod 23 after a greater or less movement 105 of the latter. By means of this controlling means and with the heating coils arranged substantially as illustrated, I can keep the temperature within the incubator substantially constant throughout all parts. 110

I do not wish to be limited to the specific form of device shown, as various changes may be made within the scope of my claims without departing from the spirit of the invention.

Having thus described my invention, I claim as new and desire to secure by Letters Patent:

1. An incubator casing having an egg-supporting shelf or tray, oppositely-disposed cleats for supporting said shelf or tray, and heating coils also supported by said cleats.
2. An incubator having oppositely-disposed walls, cleats secured to the inner surfaces thereof, a shelf or tray therein supported by said cleats and detachable therefrom, and electric heating coils also supported by said cleats.
3. An incubator having oppositely-disposed walls, cleats secured to the inner surfaces thereof, a shelf or tray supported by said cleats and detachable therefrom, and

electric heating coils also supported by said cleats and removable therefrom.

4. An incubator having oppositely-disposed cleats, an egg-supporting shelf slidably mounted thereon, a frame having sliding engagement with said cleats beneath said shelf, and a heating coil wound about said frame and presenting upper and lower heating surfaces.

5. An incubator having two egg-supporting shelves, a frame disposed intermediate said shelves, and a heating coil wound about said frame and presenting upper and lower series of parallel wires constituting heating coils.

In testimony whereof I have signed my name to this specification in the presence of two subscribing witnesses.

EDWARD AUGUST MAISCH.
